UNITED STATES PATENT OFFICE.

JAMES MERRYWEATHER, OF GREENCASTLE, INDIANA.

RAILROAD SIGNALING DEVICE.

SPECIFICATION forming part of Letters Patent No. 685,782, dated November 5, 1901.

Application filed July 26, 1901. Serial No. 69,812. (No model.)

To all whom it may concern:

Be it known that I, JAMES MERRYWEATHER, a citizen of the United States, residing at Greencastle, in the county of Putnam and 5 State of Indiana, have invented a new and useful Railroad Signaling Device, of which the following is a specification.

My invention relates to certain improvements in railroad signaling devices of that 10 class in which a passing train operates to open or close an electrical circuit containing or including an electrical bell, an annunciator, or similar alarm, and has for its object to provide an improved form of circuit-closing 15 device adapted for operation by the flanges of the car-wheel, as more fully set forth hereinafter.

In the accompanying drawings, in which similar characters of reference indicate corresponding parts throughout the various views, 20 Figure 1 is a perspective of a circuit-closing device constructed and arranged in accordance with my invention. Fig. 2 is an elevation of the same, illustrating the inclosing 25 casing in section. Fig. 3 is an end elevation illustrating a modification of the device as employed in connection with a normally open circuit, and Figs. 4 and 5 are elevations illustrating modifications of the structure.

Referring to the drawings, 1 represents a suitable base or platform secured near the outer end of a railway-tie or to the road-bed in proximity to the track 2 and being situated either outside or inside the track, as 30 may be preferred. Secured to this base are insulating-blocks 3, on which are mounted standards 5 6, having at their upper ends suitable openings, in which is journaled a rock-shaft 7, suitable collars 8 being secured to 35 said rock-shaft at points adjacent to the standards in order to prevent longitudinal movement of the rock-shaft.

Secured to or formed integral with one end of the rock-shaft is an upwardly and outwardly extending lever 9, which projects into the path of the wheel-flanges of a car travelling on the rail 2 and disposed in such manner as to be operated and depressed by each passing wheel. At the opposite end of the 45 rock-shaft is a downwardly and outwardly extended arm 10, having at its outer end a recess or opening 11 for the passage of a bolt

12, which carries a contact-block 13, the block being cushioned to some extent by a coiled spring 14, situated between its rear face and 55 the adjacent face of the arm 10.

The rock-shaft intermediate of its length is bent into crank form, as at 15, and is there connected to the ends of opposing helical tension-springs 16, secured to pins 17 on the 60 base, the function of the springs being to maintain the rock-shaft in the position illustrated in Fig. 1, with the operating-lever 9 and the contact-arm 10 in a vertical plane. Secured to the outer end of the base-plate is a curved 65 block 18, its base portion being insulated from the plate by a strip 19 of insulating material and its upper face being curved in the arc of a circle having its center coincident with the center of the rock-shaft 7. The 70 curved upper surface of the block is covered with a plate 20, of suitable conducting metal, connected to a binding-post 21, from which leads a line-wire 22, and to the standard 5 is secured a binding-post 23, to which is connected a line-wire 24, the two wires forming part of a circuit in which may be included an electromagnetic bell, annunciator, or other alarm situated at any convenient point. 75

When the parts are in position illustrated 80 in Figs. 1 and 2, the circuit is closed through the standard 5, rock-shaft 7, arm 10, block 13, and contact-plate 20, the arrangement here illustrated being designed for use in connection with a normally closed circuit. 85

In the operation of the device a passing car-wheel will strike and depress the lever 9 and through the rock-shaft move the arm 10 in the opposite direction, causing the block 13 and plate 20 to break contact and through 90 the line-wires effect the operation of the alarm.

Where the device is intended to be used on a normally open circuit, the block 18 is turned at right angles, and the contact-arm 95 10 is arranged at an angle to the vertical, with its contact-block 13 normally out of contact with the plate 20. The operation in this case is such that a slight turning of the rock-shaft, due to the contact of a passing 100 wheel-flange with the lever 9, will cause the arm 10 to move the block 13 into contact with the plate 20 and complete the circuit, the system being in this case simply changed.

from a closed to an open circuit and the apparatus described being capable of use in connection with either system with but slight modification in the arrangement of its parts.

- 5 In Fig. 4 I have illustrated a slight modification of the apparatus in which the contact-plate 20' is arranged in the arc of a circle below the contact-arm 10, the plate 20' being comparatively short, so that a slight 10 movement of the contact-arm in either direction will cause the block 13 to travel beyond the end of the plate 20' and open the circuit.

Fig. 5 illustrates a further modification in 15 which two contact-plates 20^a are arranged in the arc of the circle and separated by a block 26 of insulating material, against which latter the contact-block 13 normally rests. In this case the contact-plates 20^a are both connected to the binding-post, and a slight movement of the arm 10 in either direction will cause the block 13 to make contact with one of the plates, and thus complete the circuit of an open-circuit system.

- 25 The device is of especial value for signaling the approach of trains at railway-crossings, the bell used being placed on a post or other support at the crossing proper and connected by the line-wires to a circuit-closing device situated alongside the track at a suitable distance from the crossing. It may also be employed to signal the arrival and departure of trains from railway-stations, the circuits being arranged in connection with 30 visual or other circuits, as may be desired.

It will be understood that suitable modifications in the details of structure and the

arrangement and proportions of parts may be made within the scope of the claim without departing from my invention.

40

The device as a whole is inclosed in a casing 26', having a slot for the passage of lever 9, or the lever may be altogether outside the casing, as preferred.

Having thus described my invention, what 45 I claim is—

In a device of the class specified, a base-plate 1, standards 5, 6, carried by and insulated from said base-plate, a rock-shaft 7 journaled in said standards and having an 50 intermediate downwardly-extending cranked portion 15, opposing tension-springs 16 connected to said cranked portion and adapted to maintain the rock-shaft in proper position, an arm 9 formed at the end of the shaft 55 adapted for contact with a passing car, a contact-arm 10 disposed at the opposite ends of the rock-shaft, a yielding contact-block 13 carried by said arm, a curved block of insulating material mounted upon the base, a 60 conducting-plate 20 disposed upon the curved face of the block and adapted for contact with the block 13, and an electric circuit having its terminals connected electrically to the block 13 and the plate 20, substantially 65 as described.

In testimony that I claim the foregoing as my own I have hereto affixed my signature in the presence of two witnesses.

JAMES MERRYWEATHER.
